(57) **CLAIM**

The ornamental design for a suspension lamp, as shown and described.

DESCRIPTION

FIG. 1 is a front view of a suspension lamp with transparent globes in accordance with the present new design;

FIG. 2 is a back view of the suspension lamp of FIG. 1;

FIG. 3 is a left side view of the suspension lamp of FIG. 1; FIG. 4 is a right side view of the suspension lamp of FIG. 1;

FIG. 5 is a top plan view of the suspension lamp of FIG. 1; FIG. 6 is a bottom plan view of the suspension lamp of FIG. 1; and, FIG. 7 is an isometric view of the suspension lamp of FIG. 1.

The broken lines in the drawings illustrate portions of the suspension lamp that form no part of the claimed design.

1 Claim, 5 Drawing Sheets
